Henry Ward Beecher INVENTOR

BY
Gifford & Seal ATTORNEYS

UNITED STATES PATENT OFFICE

HENRY WARD BEECHER, OF SEATTLE, WASHINGTON, ASSIGNOR, BY MESNE ASSIGNMENTS, TO FULLER LEHIGH COMPANY, A CORPORATION OF DELAWARE

FURNACE

Application filed November 25, 1927. Serial No. 235,410.

This invention relates to a furnace for burning liquid or gaseous, or pulverized fuel, and also for burning solid fuel either alone or together with the liquid, gaseous or pulverized fuel, and will be understood from the description in connection with the accompanying drawings in which Fig. 1 is a vertical section through the furnace, partly broken away; Fig. 2 is a section along the line 10 2—2 of Fig. 1; and Fig. 3 is a section at right angles to Fig. 2 along the line 3—3 thereof.

In the drawings reference character 1 indicates an oven in front of the combustion space proper of a boiler furnace into which 15 oven solid fuel is introduced through the chute 2 and is ignited. The combustion products pass over the bridge wall 3 into the combustion space 4 of the furnace. The bridge wall 3 may be made hollow and air 20 for combustion purposes passes into it and thence through the openings 5 into the combustion space 4. The furnace has side walls 6 and a floor 7. An opening 8 is provided at the rear of the combustion space 4 immediately above the floor and a burner 9, for gas, oil or pulverized fuel, is located in the upper portion of the opening 8 and extends through the rear wall. Dampers 10 are located in the opening 8 and serve for regulating the 25 supply of air to the furnace.

A series of horizontally disposed plates 12, superposed one above the other, is located below the burner 9 with the edges of each of the plates extending farther into the furnace 35 than the one immediately above it. Each of the plates 12 may be made in sections, if desired, and brick or spacing blocks 13 of refractory material are placed between the plates 12 and spaced from each other, so as 40 to leave openings 14 through which air enters the furnace. The openings 14 are preferably so disposed that a wider series of openings is provided below the lower plates than below those near the top, as indicated 45 in Fig. 2, so that the number of air openings gradually diminishes from the lower to the upper plate 12. One edge of each of the plates 12 is supported by cross supports 15 that may be L-shaped in cross section, and 50 the ends thereof project into recesses 16 in

the walls of the furnace, and the other edges of the plates are supported by resting upon the brick or blocks 13 below the same.

The operation is as follows: When it is desired to operate the furnace with fuel from the burner 9 only, the dampers 10 are regulated so as to provide the proper amount of air for the combustion, and the openings provide for proper distribution of the air. Any ash or slag that falls upon the projecting 55 edges of the plates 12 can be removed by simply pushing the same off through the holes 14 so that the air passages will not become blocked. When it is desired to burn solid fuel, the same is introduced into the oven 60 through the chute 2. Cinders that pass over the bridge wall 3 and fall upon the plates 12 will burn and the ashes that collect upon these plates can be removed as above described 65 so that combustion air will have access to the fuel entering through the burner 9, as desired. It will be obvious that both solid fuel and fuel introduced through the burner 9 can be burned in this furnace at the same time. The furnace is especially useful in 70 burning waste products from paper mills or saw mills or waste bagasse from sugar plants, or any other furnace wherein two different types of fuel are to be burned independently 75 in different portions of the furnace enclosure, either concurrently or alternatively. 80

I claim:

1. In combination, a furnace, an oven for burning solid fuel in front of said furnace, a passageway for the hot products of combustion from said oven to said furnace, a fuel burner, and a plurality of air supply ducts with ledges above them extending progressively into said furnace below said burner to receive ashes and other material from said 85 oven.

2. In combination, a furnace, an oven for burning solid fuel in front of said furnace, a bridge wall between said oven and said furnace, a passageway for the hot products of combustion from said oven to said furnace over said bridge wall, a fuel burner, and a plurality of air supply ducts with ledges 95 above them extending progressively into said 100 oven.

furnace below said burner to receive ashes and other material from said oven.

3. In combination, a furnace, an oven for burning solid fuel in front of said furnace, a passageway for the hot products of combustion from said oven to said furnace, a hollow bridge wall between said oven and said furnace provided with air ports into said furnace, a fuel burner, and a plurality of air supply ducts with ledges above them extending progressively into said furnace below said burner to receive ashes and other material from said oven.

4. In a furnace, a fuel burner, and a series of rectangularly shaped air supply ducts extending horizontally into said furnace below said burner, said ducts being arranged in rows with the lower rows wider than the upper ones and being made up of superposed plates each extending into said furnace farther than the one above it with vertical partitions between said plates.

5. In a furnace, a burner adapted to project a stream of combustible material into said furnace, and a series of parallel air supply ducts extending into said furnace to different distances below said burner, said ducts being formed by parallel plates with spacing blocks between them.

30 HENRY WARD BEECHER.
